UNITED STATES PATENT OFFICE.

HORATIO G. GILLMOR, OF WASHINGTON, DISTRICT OF COLUMBIA.

ANTICREEPER.

Application filed July 7, 1925. Serial No. 42,095.

My invention relates to devices for preventing the longitudinal creep of railroad rails, such devices being commonly known as rail anchors, anticreepers, creepchecks or 5 rail stays.

The principal object of the invention is to provide a device of this type, which will be simple in its construction, inexpensive to manufacture, light in weight, strong and capable of taking a firm and reliable hold upon the rail. A further object is to provide a device constructed in one piece which may be quickly and conveniently applied to the rail with the tools usually employed by 10 track mechanics and will not be loosened or become ineffective by vibrations, movement of the rail temporarily in a direction the reverse of that in which the rail tends to creep or any of the other causes tending to 15 loosen the grip of rail anchors on the rails engaged thereby.

My rail anchor possesses other features of novelty and advantage, which, with the foregoing will be obvious from the following 20 description.

One embodiment of the invention is shown in the accompanying drawings, in which:

Figure 1 is an elevation, with the rail in section, showing the device in position.

Figure 2 is a side elevation of the same with the crosstie shown in section.

Figure 3 is an elevation, with the rail in section, illustrating the method of applying the device.

Figure 4 is a section at the plane indicated by the line A A in Figure 1.

Figure 5 is a perspective view of the device.

In the drawings B is a rail of the usual 40 construction, having a base flange C which rests upon the crossties one of which is shown in section at D.

The improved rail anchor consists essentially of a bar E the middle portion I of 45 which is straight and arranged to grip the bottom of the base flange C. At each side of the portion I of the bar E tie engaging portions K and L are formed by bending the bar E downwardly and then upwardly.

One end of the bar E is brought to substantially right angles to the portion I to form a retaining portion M; which, when the rail anchor is in position on the rail, will extend somewhat above the bottom of the base of 50 the rail. The other end of the bar E is made much longer and bent over to form an arm

H adapted to engage and grip the upper surface of the base flange C at one side of the rail.

In forming the several portions of the bar E I prefer to form one face of the portion I, gripping the bottom of the base flange C, and the face of the arm H, gripping the upper surface of the base flange C, to be concave as shown at F; at the same time 60 making the other face of the bar E for these portions convex as shown at G. If desired a rolled bar having one side concave and the other convex might be employed. By so shaping the bottom gripping portion I and 65 the arm H, engagement of each with the base flange C is at the edges Q and R for the portion I and along the edges O and P for the gripping arm H.

In shearing the bar to form the rail anchor it may be sheared on a bevel as shown at N leaving the other end with the reverse bevel. This provides a surface N, which will engage the lower corner of the base flange C while the rail anchor is being 70 forced into position to keep the anchor from jumping off the rail if repeated blows are necessary to drive it to position.

The rail anchor is applied to the rail from one side, the arm H engaging the top of the base flange C at its end only and the lower corner of the base flange C at the other side of the rail being then engaged by the bevel end N; and driving the whole transversely upon the rail until the retaining portion M 90 can reach its final position with the face S engaging the vertical edge of the base flange C at the side opposite to that engaged by the arm H. The bottom gripping portion I and the arm H are so disposed with relation 95 the one to the other that, as the bar E is forcibly moved transversely upon the rail the edges O and P of the arm H ride upon the top of the base flange C and the edges Q and R of the bottom gripping portion I ride upon the bottom of the base flange C; and one side of the base flange C of the rail B is wedged in between the arm H and the portion I securely.

In the final position of the rail anchor on the rail shown in Figures 1 and 2 the base flange C is firmly gripped between the portion I and the arm H, which engages and grips the upper surface for the greater portion of the length of the arm H; and is held against displacement from position by the engagement of the surface S of the retaining 105 110

portion M with the opposite edge of the base flange C.

The direction in which the rail tends to creep is indicated by the arrow in Figure 2.

5 Such creeping movement is resisted and prevented by the engagement of the faces of the portions K and L with the crosstie D; which, by their form, not only provide ample surface of contact with the tie, but also provide contact with the tie D at a considerable distance below the bottom of the base flange C of the rail B.

10 It will readily be seen that by making the bar E relatively wide as shown in Figures 15 2 and 5 and by forming the faces of the base flange gripping arm H and the bottom gripping portion I to present concave surfaces to the rail base and engage the rail base along the edges Q and R of the portion I and O 20 and P of the arm H there is provided a construction in which the pressure is exerted along the edges O and P and Q and R, tending to flatten the section of the arm H and the bottom gripping portion I as indicated 25 in the section at the plane A-A in Figure 1 shown in Figure 4, where the dotted lines indicated, greatly exaggerated, the shape of the section before the rail anchor has been forced into position and the full lines indicate the sections after being flattened by the pressure exerted along the edges O and P of the arm H and Q and R of the bottom gripping portion I. The effect will readily be understood to produce a very effective and 30 permanent grip of the arm H upon the top of the base flange C and of the portion I upon the bottom of the base flange C.

35 To remove the rail anchor from the rail, the retaining portion M is forced downward 40 until the lower corner of the base flange C will engage the surface N and the whole then driven transversely of the rail in the direction the reverse of that in which the rail anchor was forced onto the rail.

45 I claim:

1. An anticreeper, comprising a bar formed with an arm at one end adapted to engage and grip the upper surface of the rail base along the edges of the arm only and to be 50 out of contact with the rail base between the edges thereof, a body portion adapted to grip the bottom of the rail base, a tie-engaging portion and an end retaining portion.

55 2. A rail anchor, comprising a rolled bar of relatively greater width than thickness having one side concave and toward the rail bent to form an arm gripping the top of the rail base along the edges of said arm, a portion adapted to grip the bottom of the rail 60 base along the edges of said portion and a portion adapted to engage a tie in opposition to the tendency of the rail to creep.

65 3. A rail anchor comprising a transversely concave body having at one end a tie-engaging portion and a flange gripping portion

adapted to exert gripping pressure upon the rail flange when driven thereon and at the other end retaining means for holding the rail anchor in position.

4. An anticreeper comprising a transversely concave body having tie-engaging elements at the two ends thereof, a flange gripping element constructed to exert gripping pressure upon the rail when driven thereon at one end and retaining means at 75 the other end for holding the anticreeper in position.

5. A rail anchor formed of a single piece of metal provided at one end with an arm adapted to engage the upper surface of a 80 rail flange along the edges of said arm only and with a depending tie-engaging portion.

6. An anticreeper comprising a single piece of metal provided with depending tie-engaging means, an arm at one end arched in 85 cross section and adapted to engage the top of a rail flange along the edges only of said arm and retaining means for holding said arm to the rail base.

7. A rail anchor comprising a single piece 90 of metal provided with depending portions adapted to engage a tie, an arm at one end presenting a concave surface and adapted to bear upon the top of the rail flange along the edges of said arm only and retaining 95 means for holding the device to the rail base at the other end.

8. An anticreeper comprising a body 100 adapted to engage the bottom of the rail base along the edges of said body only transversely of the rail provided at one end with a flange gripping element arranged to exert gripping pressure upon the top of a rail flange when driven thereon and with depending tie-engaging means.

9. A rail anchor comprising a body, arched in cross section and arranged to engage the bottom of a rail base transversely along the edges of said body, depending tie-engaging means and an arm, arched in cross section 110 and arranged to engage the top of a rail flange along the edges of said arm only and to exert gripping pressure thereon when driven onto the flange at one end and retaining means for holding the device to the rail 115 base at the other end.

10. A rail anchor comprising a single bar 120 of metal which is arched in cross section and arranged to bear against the rail base along the edges of said bar only provided with tie-engaging means, a portion adapted to engage and grip the top of the base flange at one side and a portion adapted to engage the edge of the base at the other side of the rail.

11. In a rail anchor, an anchor body having concave surfaces disposed toward the rail whereby engagement with the rail along the edges of said body only is effected.

12. An anticreeper comprising a concave bar having the concave surface thereof dis- 130

posed toward the rail whereby engagement of said bar with the rail along the edges of said bar only is effected and the stresses set up when said anticreeper is forced into position on the rail tend to flatten said bar.

13. A rail anchor of concave cross section adapted to be applied to the rail with its concave surface adjacent the rail and comprising a looped member embracing one flange, a tie-engaging member and a member engaging the other flange for retaining the rail anchor in position on the rail.

14. A rail anchor concave in cross section adapted to be placed on the rail with its concave face toward the rail whereby the strains set up in said rail anchor when forced into position on the rail tend to reduce its concavity.

15. An anticreeper concavo convex in cross section adapted to be placed on the rail with its convex face away from the rail and its concave face next the rail whereby the stresses set up in said anticreeper when forced into position on the rail tend to flatten said anticreeper.

16. A rail anchor having a body portion of concavo convex cross section and adapted to be applied to the rail with its concave surface next to the rail and having also tie-engaging and rail engaging portions, the last named being strained and flattened when the rail anchor is applied to the rail.

17. A rail anchor having a body portion of concavo convex cross section adapted to be applied to the rail with the concave surface toward the rail bottom and to be flattened under the stresses set up when the rail anchor is applied to the rail and having also rail base flange engaging means.

18. A rail anchor including a spring bar 40 of concavo convex cross section adapted to be applied to the rail with its concave face disposed toward the rail and having rail-engaging and tie-engaging means.

19. A rail anchor including a spring bar 45 having one face concave and disposed toward the rail whereby said bar is in contact with the rail at the edges of the bar only when applied to the rail and having tie-engaging means.

20. A rail anchor consisting of a bar having a concavo convex cross section adapted to be applied to the rail with its concave face adjacent the rail having rail-engaging portions which are strained and flattened 55 when said rail anchor is forced into position on the rail.

21. A rail anchor comprising a resilient clamp of concavo convex cross section throughout its length.

22. A rail anchor comprising a tie-abutting body of concavo convex cross section throughout and having a rail gripping jaw at one end and rail base engaging means at the other end.

23. An anticreeper comprising a tie-abutting body of concavo convex formation throughout having a gripping jaw at one end and retaining means for holding said anticreeper in place at the other end.

24. A rail anchor comprising a self locking resilient clamp of concavo convex section throughout which engages the rail along the edges of said clamp and is strained and flattened when forced into position on 75 the rail.

H. G. GILLMOR.
